IRVING McDOWELL, OF BROOKLYN, NEW YORK.

ATTACHMENT FOR INTERNAL-COMBUSTION ENGINES.

Application filed May 29, 1923. Serial No. 642,160.

To all whom it may concern:

Be it known that I, IRVING McDOWELL, a citizen of the United States, and resident of the borough of Brooklyn, county of Kings, city and State of New York, have invented certain new and useful Improvements in Attachments for Internal-Combustion Engines, of which the following is a specification.

10 My invention relates to internal combustion engines and has for its object to provide an attachment adapted more particularly to increase the efficiency of the customary spark plugs and to protect the same against 15 the accumulation of oil and carbon. The invention will be fully described in the description hereinafter in which more specific objects thereof will appear.

Reference is to be had to the accompanying drawings which illustrate several examples of the invention without defining its limits and in which Fig. 1 is a sectional view of one form of the attachment showing the same in operative position in an internal combustion engine; Fig. 2 is a cross section on the line 2—2 of Fig. 1; Fig. 3 is an end view thereof; Fig. 4 is a longitudinal section of another form of the attachment; Fig. 5 is a cross section on the line 5—5 of Fig. 4 and 30 Fig. 6 is an end view thereof.

As shown in Figs. 1, 2 and 3 the attachment comprises a casing consisting of a body 10 of generally cylindrical form and provided with a hexagonal or equivalent head 11 for the accommodation of a wrench or other suitable tool, said body having an interior screw-thread 12 for the accommodation of the screw-threaded end 13 of the spark plug 14. An externally screw-threaded neck 15 projects in an axial direction from the casing 10 and has its free end preferably tapered, as indicated at 16 and provided with apertures 17 which communicate with an interior axial passage 18. The latter extends from the apertured end 16 to the interior of the casing 10 which constitutes an auxiliary explosion chamber 19 in which the electrodes 20 of the spark plug 14 are contained as shown in Fig. 1. The 50 surface of the passage 18 is roughened in any suitable manner as, for instance, by being provided with screw-threads as shown in Fig. 1, the purpose of which will appear more fully hereinafter; the apertures 17 con-

verge toward the passage 18 and extend 55 along lines which intersect each other as shown in Fig. 1.

In practice the attachment is connected with the engine by screwing the neck 15 thereof into the customary spark plug opening in the cylinder 21 so that the tapered end 16 extends into the combustion chamber thereof and the apertures 17 establish communication between said combustion chamber and the passage 18, it being understood 60 that the spark plug 14 occupies the position shown in Fig. 1. With this arrangement the attachment is interposed between the combustion chamber of the engine and the spark plug, the electrodes 20 of which 65 are contained in, and protected by, the auxiliary explosion chamber 19. In operation, under the compression stroke of the piston, explosive mixture is forced through the apertures 17 and the passage 18 into the 70 auxiliary combustion chamber 19 and at the proper time is there ignited by the spark produced in the well known way at the electrodes 20. The explosion of this auxiliary charge, contained in the auxiliary chamber 19, results in a burning mixture which 75 is projected through the aperture 17 in a plurality of jets of intense flame whereby the main charge of explosive mixture contained in the combustion chamber of the engine is efficiently and completely exploded to 80 produce the operation of the engine in the well known way.

In the form shown in Figs. 4, 5 and 6, the attachment comprises a hexagonal body 85 11^a from which an externally screw-threaded neck 15^a projects which, in turn, is continued in the form of a cylindrical extension 10^a, the end surface 16^a of which is perfectly flat as shown in Fig. 5. The cylindrical extension 10^a is provided with a plurality of apertures 17^a which, in this form, 90 extend at right angles to the axis of the attachment and communicate with an interior passage 18^a which, in turn, communicates with the auxiliary explosion chamber 19^a as in the first form. The auxiliary explosion chamber 19^a encloses the electrodes 95 20 of the spark plug 14 in the same way as in the form first described, said spark plug 100 being combined with the attachment by having its screw-threaded neck 13 engage with the interior screw-threads 12^a of said auxil-

iary combustion chamber as shown in Fig. 4. The passage 18^a preferably has its surface roughened in the same way as in the form illustrated in Fig. 1, for instance, by 5 being provided with screw-threads.

- In practice the form now being described is attached to the engine by having the screw-threaded neck 15^a screwed into the customary spark opening of the cylinder 10 21, the arrangement and dimensions of the parts being such that the apertures 17^a lie in close proximity to the interior surface *a* at the upper end of the cylinder when the attachment is in place thereon.
- 15 In operation a portion of the explosive mixture is forced inwardly through the apertures 17^a and the passage 18^a into the auxiliary explosion chamber 19^a in which it is exploded at the proper time as in the 20 first form and is projected outwardly through the apertures 17^a in the form of jets of intense flame which serve to explode the main charge in the combustion chamber of the engine as in the first form. Because 25 of the location and direction of the apertures 17^a, these jets of flame are projected along the inner end surface of the cylinder and thus burn away any oil which may have adhered to this surface and at the same time 30 keep the carbon deposit on said surface at a low point.

In both forms of the invention the apertures 17 and 17^a extend transversely to the axis of the attachment so that the mixture 35 passing inwardly through the same is churned up as it were within the passage 18 or 18^a so that any oil carried by this mixture is separated therefrom. Because of the roughened surface of this passage 18 or 40 18^a this oil, together with any oil which may not have been physically separated from the mixture, clings to said roughened surface and is prevented thereby from reaching the auxiliary explosion chamber 19 or 19^a. The 45 oil collected, in this way, upon the roughened surface of the passage 18 or 18^a, is blown out through the apertures 17 or 17^a with each explosion of the mixture in the auxiliary chamber 19 or 19^a so that the electrodes 50 20 are at all times kept perfectly dry and free from oil and therefore in a condition of maximum efficiency as an igniting medium. In both forms the apertures 17 and 17^a are so dimensioned and positioned with 55 respect to each other as to leave a minimum amount of metal between each two holes, which metal becomes quickly heated by the successive explosions and preheats the mixture which passes inwardly through said 60 apertures 17 and 17^a and by this preheating increases the explosibility thereof.

The externally screw-threaded necks 15 and 15^a are of such an axial length as to position the inner end of the attachment in 65 the internal combustion chamber in such

a way that there will be no interference with the operation of the piston or the customary valves.

The inner end face 16, and more particularly the inner end face 16^a, serves to deflect 70 the mixture as the same is being compressed by the piston and consequently forces said mixture inwardly through the apertures 17 and 17^a along a sinuous path and thereby helps to clean the same of any foreign matter and more particularly of any oil which may be carried thereby.

The attachment is simple in construction and efficient in operation and maintains the electrodes of the spark plug in a condition of 80 maximum serviceability and requires no skill in its attachment to the engine; the attachment is simply screwed into the customary spark plug opening in the same way that the spark plug is fixed therein after 85 which the spark plug is connected with the attachment in the manner set forth. The use of the attachment requires no special construction in the engine and requires no 90 changes to be made therein.

The attachment which is in the nature of a shield protects the spark plugs from oil and carbon and, as a matter of fact, prevents carbon caused by excessive oil or a slow burning mixture; the attachment increases the life of the plugs by protecting them from the heat of the cylinder head which, in many cases, warps the electrodes and either closes them up or opens them apart and, in any case, interferes with the 100 efficiency of the ignition system. Furthermore the porcelain of the plugs is kept away from the intense heat of the cylinders and is thereby guarded against cracking. The attachment makes the starting of the 105 engine easier because the gas in the auxiliary explosion chamber 19 is ignited with one turn of the motor on the compression stroke and incidentally sends forth a powerful burst of flame into the cylinder similar to the flame of a blow-torch which will 110 ignite either a lean or rich mixture much quicker and more positively than the ordinary spark of the customary spark plug will do it; at the same time every particle 115 of the mixture, including any oil or other foreign matter which may be suspended therein or carried thereby will be completely consumed. The life of the spark plugs and of the entire car, as a matter of 120 fact, is extended and the engine is given more power and increased flexibility. The possibility of loose bearings, loose wrist pins, universal joints, keyways, loose keys, and loss of power caused by foul spark 125 plugs, is also done away with.

Various changes in the specific form shown and described may be made within the scope of the claims without departing from the spirit of my invention.

I claim:

1. An attachment for internal combustion engines comprising a member adapted for connection with an engine cylinder so as to communicate at its inner end with the combustion chamber thereof and to receive a spark plug at its outer end in a manner to position the electrodes thereof at a distance from said inner end, said member, at its inner end, having apertures extending transversely to its major axis, and having its interior surface roughened in proximity to said apertures and between its inner end and the point at which the spark plug electrodes are intended to be located.
2. The combination of a spark plug and a casing connected therewith and covering the electrodes thereof, said casing being adapted for connection with the cylinder of an internal combustion engine and having apertures at its inner end for communication with the combustion chamber of said engine and further being provided with an axial passage extending inwardly from said apertures toward said electrodes and having its surface roughened, said roughened surface being located between said apertures and said electrodes.
3. The combination of a spark plug and a casing connected therewith and covering the electrodes thereof, said casing being adapted for connection with the cylinder of an internal combustion engine and having apertures at its inner end, said casing further having an interior auxiliary explosive chamber in which said electrodes are located and an axial passage extending from said chamber to said apertured end and having its surface roughened, said roughened surface being located between said apertures and said electrodes.
4. The combination of a spark plug and a casing connected therewith and covering the electrodes thereof, said casing being adapted for connection with the cylinder of an internal combustion engine and having a tapered inner end provided with apertures, said casing further having an interior auxiliary explosion chamber in which said electrodes are located and an axial passage extending from said chamber to said apertured end and having its surface screw-threaded to provide a roughness thereon, said screw threaded surface being located between said apertures and said electrodes.

In testimony whereof I have hereunto set my hand.

IRVING McDOWELL.
